ELECTRICAL TERMINAL BLOCK

John A. Toedtman, Warson Woods, St. Louis, Mo., assignor to ITT Blackburn Corporation, St. Louis, Mo., a corporation of Delaware

Filed May 3, 1967, Ser. No. 6,933

Term of patent 14 years

(Cl. D26—1)

FIG. 2

FIG. 1

FIG. 3

FIG. 4

FIG. 5

FIG. 1 is a front elevational view of an electrical terminal block, showing my new design;

FIG. 2 is a top plan view thereof;

FIG. 3 is a bottom plan view thereof;

FIG. 4 is a rear elevational view thereof, opposite to the side shown in FIG. 1, and

FIG. 5 is an end view thereof.

I claim:

The design for an electrical terminal block, substantially as shown and described.
